Application October 29, 1948, Serial No. 149,378

Term of patent 14 years

(Cl. D42—7)

To all whom it may concern:

Be it known that I, Thomas G. Haney, a citizen of the United States, residing at Eau Claire, in the county of Eau Claire and State of Wisconsin, have invented a new, original, and ornamental Design for a Timer or Similar Article, of which the following is a specification, reference being had to the accompanying drawings, forming a part thereof.

In the drawings:

Fig. 1 is a top plan view of a timer or similar article showing my new design;

Fig. 2 is a front elevation of the same;

Fig. 3 is a side elevation thereof;

Fig. 4 is a rear elevation; and

Fig. 5 is a bottom plan view of the timer or similar article shown in Fig. 1.

I claim:

The ornamental design for a timer or similar article, as shown.

THOMAS G. HANEY.
